UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

COUPLER-OPERATING DEVICE

Application filed July 26, 1928. Serial No. 295,426.

An object of the invention is to support the inner end of the revoluble rod of a coupler operating device solely upon the coupler so that the coupler head may move laterally 5 and longitudinally of the car in service without affecting the relation of the component parts of the coupler operating device, whereby the effective force transmitted by the revolution of the operating rod to the coupler lock lifter is neither increased nor decreased by the service movements of the coupler.

Another object of the invention is to provide means, supported solely by the coupler and held in position by the lock lifter, to retain the operating rod in proper operative position upon the coupler.

In the drawings:

Fig. 1 shows a typical application of the device to a car coupler.

Fig. 2 is a front elevation of Fig. 1.

Fig. 3 is a plan view of Fig. 1 showing also a part of the car.

Fig. 4 shows the relation of the parts of the operating device when the lock lifter of the coupler is in raised position.

Fig. 5 shows the relation of the parts of the operating device when the coupler is in "lock set" position.

Fig. 6 shows the relation of the lock lifter eye and the link.

Figs. 7 and 8 show a modified form wherein the projections are formed on a separate member.

The standard vertical plane coupler (known as A. R. A. type) has a knuckle 2 pivoted to the coupler head 3 and provided with a tail behind which the lock is placed. The lock lifter 4 protrudes through and above the coupler head and is provided with a horizontally positioned eye. This lock lifter eye is $1\frac{1}{16}$ " in diameter and its axis is perpendicular to the longitudinal center of the car. This size and position has been determined by the A. R. A. and is standard for the majority of couplers now in service. The

lock lifter is arranged to move in substantially a vertical plane to operate the parts within the coupler head, such operation consisting of unlocking the knuckle, throwing the knuckle and assuming a lock set position.

The preferred form of the device comprises an operating rod 6 revolvably mounted in a bracket 7 positioned adjacent the side of the car and having a handle 8 or other means to revolve it. The inner end of this rod rests upon the coupler so that as the rod is revolved it bears and fulcrums solely upon the coupler (at 9). A preferably channel link 10 straddles the upper portion of the lock lifter 4 and is secured thereto by a horizontal pin 11 forming a pivotal connection therewith. The flanges of the channel link loosely fit against the side walls of the lock lifter to prevent the link from moving laterally out of the vertical plane and the web of the channel engages the back portion of the lock lifter to prevent the link swinging backwardly beyond alignment with the lock lifter. This arrangement may be called a "knee connection" and prevents the collapsing of the device.

The operating rod preferably bears on the coupler behind the lock lifter and is extended and formed so that a portion 12 thereof is in front of the lock lifter and a strut 13 is pivotally connected to this portion 12 of the operating rod and to the upper portion of the link 10 so as to form a flexible connection therebetween. This strut 13 preferably has an elongated bearing 14 upon the operating rod to assist in retaining the component parts of the device in a substantially vertical plane so as to prevent them from collapsing.

This invention is an improvement upon the construction shown and claimed in my co-pending application for patent, Serial No. 277,368, filed May 12, 1928, the improvement consisting of the projection 30 positioned between the operating rod 6 and the lock lifter 40

4, so that the rod cannot slip forward (as shown in Fig. 4 of the above mentioned application) and bear against the lock lifter and cause friction, thus increasing the power necessary to operate the device. Furthermore, when the coupler is released from lock set position the link 10 might rest upon the rod 6 and prevent the lock lifter from falling far enough to allow the lock to lock the coupler. A further object of this projection is to give greater assurance that the parts will fall by gravity to their respective normal positions when released from their extreme elevated positions as shown in Fig. 4.

15. A further improvement upon the construction of application No. 277,368, filed May 12, 1928, consists in the use of the rear projection 31 which is positioned between the projection 30 and the striking surface 32 of the 20 coupler horn. Both projections 30 and 31 are positioned between the striking surface 32 of the coupler horn and the lock lifter 4. This projection prevents the rod 6 from slipping back beyond the coupler horn striking surface where it might be damaged by being mashed between the coupler horn and the adjacent part of the car 33. A spring cotter 25 and other similar means is used to retain the rod in its proper relation to the projection or projections.

Figs. 7-8 shows a modified form wherein a separate member 39 is used as a support-bracket. This support-bracket comprises a horizontal base plate 43 provided with an aperture 44 which preferably fits snugly around the lock lifter. The projections 40-41 are integral with the base plate 43 and serve the same functions as projections 30-31 heretofore described. When this support-bracket is in place and the operating device connected to the lock lifter, the bracket requires no other attachment to hold it in place, and furthermore the operating rod 6 is always in proper relative position to the lock lifter.

45. In the operation of the device the operating rod 6 is revolved which raises the outer portion 12 thereof and through the medium of the strut 13 raises the link 10 and pulls the lock lifter 4 up with it, as shown in Fig. 4.

Fig. 5 shows the relation of the associated parts of the device when the coupler is in "lock set" position, that is, when the lock lifter 4 is retained in a raised position by parts within the coupler and the operating rod 6 returns to its normal position and the link 10 and strut 13 assume the positions shown.

50. The portion 12 of the operating rod which is positioned in front of the lock lifter prevents the operating rod from being revolved too far, as shown in this Fig. 4; furthermore, the knee connection (referred to above) prevents the link 10 from falling backward.

55. The relation of the associated parts is such

that when the handle 8 of the operating rod is released the rod will return to its normal position by gravity. The operating rod is bent, as shown in Fig. 3, so that the preponderance of weight will be on the outside of a line drawn between the two supporting bearings (7 and 9) which causes a tendency for the handle to fall into substantially vertical position and the inner end of the operating rod to return to the horizontal position shown in Figs. 1 and 5.

60. I prefer to have the crank arm in substantially a horizontal position when the device is in normal position, as shown in Fig. 1.

Some difficulty has been experienced by the 65 wearing of the parts within the coupler head permitting the lock lifter 4 to drop sufficiently to catch on the interior wall 45 and become wedged, making it difficult (and in extreme cases impossible) to raise the lock lifter. The 70 support-bracket 39 (see Figs. 7-8) has the further object of supporting the lock lifter to a predetermined elevation (depending upon the thickness of the base plate 43) so that, even though worn, it cannot become 75 bound within the coupler head. This device can be applied without removing the lock lifter from the coupler or removing the operating device from the car.

The accompanying drawings illustrate the 80 preferred form of the invention, though it is to be understood that the invention is not limited to the exact details of construction shown and described, as it is obvious that 85 various modifications thereof within the 90 scope of the claims will occur to persons skilled in the art.

I claim:

1. A device for operating a car coupler comprising a coupler lock lifter, a bracket 105 engaging the lock lifter and provided with a projection, a revoluble operating rod fulcruming upon said bracket behind the projection, said rod provided with a crank arm, 110 a link having a knee connection with the lock lifter and with its upper end above the crank arm, and a strut pivotally connected to the operating rod crank arm and to the upper part of the link.

2. A device for operating a car coupler comprising a coupler lock lifter, a bracket 115 engaging the lock lifter and provided with a pair of spaced apart projections, a revoluble operating rod fulcruming upon said bracket between said projections, said rod provided with a crank arm, a link having a knee connection with the lock lifter and with its upper end above the crank arm, and a strut pivotally connected to the operating rod crank arm and to the upper part of the link.

3. A device for operating a car coupler comprising a coupler lock lifter, a bracket 120 engaging the lock lifter and provided with a projection, a revoluble operating rod fulcruming upon said bracket behind the pro- 125

jection, said rod provided with a crank arm, a link having a knee connection with the lock lifter and with its upper end above the crank arm, and a strut pivotally connected to the operating rod crank arm and to the upper part of the link, the lower end of the link engaging the bracket when the device is in normal position so as to support the lock lifter in a predetermined elevation.
